TOY CATAPULT

John A. Riordan, Denver, Colo.

Application January 24, 1952, Serial No. 18,190

Term of patent 7 years

(Cl. D34—15)

To all whom it may concern:

Be it known that I, John A. Riordan, a citizen of the United States, residing at Denver, State of Colorado, have invented a new, original, and ornamental Design for Toy Catapult, of which the following is a specification, reference being had to the accompanying drawing, forming a part hereof.

Figure 1 is a side elevation of a toy catapult showing my new design;

Figure 2 is an edge view thereof; and

Figure 3 is a section taken in line 3—3 of Figure 1.

I claim:

The ornamental design for a toy catapult, as shown.

JOHN A. RIORDAN.
